Daniel P. O'Keefe and Louis J. Smallen,
Los Angeles, Calif.

Application March 12, 1934, Serial No. 51,032

Term of patent 7 years

To all whom it may concern:

Be it known that we, DANIEL P. O'KEEFE and LOUIS J. SMALLEN, citizens of the United States, residing at Los Angeles, in the county of Los Angeles and State of California, have invented a new, original, and ornamental Design for a Guard Rail for Stoves, of which the following is a specification, reference being had to the accompanying drawing, forming part thereof.

Figure 1 is a perspective view of the guard rail, showing our new design.

Figure 2 is a perspective view of the guard

rail illustrating it as it appears when attached to a stove, the stove being indicated in dotted lines.

The stove indicated in the drawing in dotted lines is not a part of the invention and is not claimed.

We claim:

The ornamental design for a guard rail for stoves as shown and described.

DANIEL P. O'KEEFE.
LOUIS J. SMALLEN.
